[57] CLAIM

I claim the ornamental design for a card tray, as shown and described.

DESCRIPTION

FIG. 1 is a perspective view of a card tray;
FIG. 2 is a front view of the card tray shown in FIG. 1;
FIG. 3 is a rear view of the card tray shown in FIG. 1;
FIG. 4 is a right side view of the card tray shown in FIG. 1 with the left side view being the same;
FIG. 5 is a top view of the card tray shown in FIG. 1;
FIG. 6 is a bottom view of the card tray shown in FIG. 1;
FIG. 7 is a perspective view of an alternative embodiment of the card tray shown in FIG. 1;
FIG. 8 is a front view of the card tray shown in FIG. 7;
FIG. 9 is a rear view of the card tray shown in FIG. 7;
FIG. 10 is a right side view of the card tray shown in FIG. 7 with the left side view being the same;
FIG. 11 is a top view of the card tray shown in FIG. 7; and,
FIG. 12 is a bottom view of the card tray shown in FIG. 7. The broken lines showing portions of the card tray in FIGS. 1-12 are for illustrative purposes only and form no part of the claimed design.
